SHINGLE PAINTING AND STAINING
MECHANISM

Mark H. Jenkins, Sr., Kansas City, Mo.

Application September 11, 1934, Serial No. 743,505

10 Claims. (Cl. 91—39)

My invention relates to a shingle painting and staining mechanism and my object is to provide a simple, inexpensive and efficient mechanism of this character for automatically applying paint, stain, or other liquid in a uniform manner to shingles.

In carrying out my invention I employ a relatively long housing and a conveyer for conducting the shingles through said housing. During passage of the shingles through the housing the paint or stain is applied to one or both sides, as preferred, of each shingle and then smoothed off to provide a uniform coating during which operation the surplus paint or stain is also removed.

Adjustable means are provided for exposing more or less of the area of the shingles to the action of the paint or stain applying means, so that, for instance, almost the entire area may be coated or only that portion may be coated which is to be exposed to the weather when the shingles are applied to a roof.

Means are also provided for thoroughly mixing the ingredients constituting the paint or stain while the mechanism is in operation so that the color may be uniform and all of the shingles will present the same appearance when coated.

Means are also provided for forcing the contents of the mixer to the paint or stain applying means and for collecting and returning the surplus paint or stain to the mixer for reuse.

In order that the invention may be fully understood, reference will now be had to the accompanying drawings, in which:

Fig. 1 is a perspective view of the mechanism.

Fig. 2 is a side elevation with the walls of the housing in cross section to show the mechanism installed within said housing.

Fig. 3 is an enlarged vertical cross sectional view on line 3—3 of Fig. 2.

Fig. 4 is a fragmentary plan view of a draining means for returning the surplus paint or stain to the mixer for reuse.

Fig. 5 is a plan view of the paint or stain mixer.

Fig. 6 is a vertical sectional view of one of the brushes for applying paint or stain to the shingles.

Fig. 7 is a cross section on line 7—7 of Fig. 6.

Fig. 8 is a broken horizontal sectional view of a portion of the housing with the paint mixer swung outwardly therefrom.

Fig. 9 is a detail cross section of a portion of a conveyer with the driving mechanism thereof in elevation.

Fig. 10 is a detail perspective view of a shield which may be employed when the shingles are to be given variegated colors.

Fig. 11 is a fragmentary perspective view of a portion of the conveyer.

In carrying out the invention I employ a suitable housing 2 consisting in the present instance of a skeleton frame 4 inclosed in sheet metal or other suitable walls 6. The housing 2 is mounted upon casters 5 so that it may be readily moved and its bottom portion is reinforced with a bed plate 4a to carry certain mechanism hereinafter described.

8 designates a conveyer comprising a pair of endless belts 10 each of which runs around a pair of pulleys 12 operably mounted upon the upper portion of the housing 2. The belts 10 are arranged side by side and close together to frictionally engage and carry the shingles A from the front to the rear of the housing 2.

The belts 10 extend substantially the full length of the housing 2 and may be provided with spurs 14, Fig. 11, to more reliably hold the shingles A from displacement during their progress through the housing 2. One of the belts 10 is driven by suitable mechanism and drives the companion belt by frictional contact with the intervening shingles A. The driving mechanism consists in the present instance, of a shaft 16 upon which one of the pulleys 12 is fixed, bevel gear wheels 18 and 20, pulleys 22 and 24, an endless belt 26 and a motor 28.

30 designates a guide for holding the upper edges of the shingles A in horizontal alignment while passing through the housing 2. The guide 30 is adjustably supported above the housing 2 so that it may be raised or lowered to accommodate shingles of different lengths and also act as a gage in determining how large an area of each shingle is to be exposed to the paint or stain. The guide 30 is supported by studs 32 and nuts 33. The studs 32 are supported by brackets 34 secured to the top of the housing 2 and provided with longitudinal slots 36 to permit the studs 32, 40 which project therethrough, to move up and down with the guide member 30 when the nuts 33 are loosened. As shown by Figs. 1 and 2 the forward end of the guide 30 projects beyond the front end of the housing 2 and cooperates with a short 45 guide 38 in directing the shingles A through an inlet slot 40 in said front end. The guide 38, like the guide 30, is adjustable up and down to accommodate shingles of different lengths and for that purpose is secured to the housing by means of set screws 42 which extend through a vertical slot 44 in the guide 38. The rear wall of the housing is provided with an outlet slot (not shown) similar to the inlet slot 40 and communicating with the latter through a slot 56 extending longitudi- 50 55

nally through the top of the housing 2 for the passage of the shingles.

The paint or stain is applied to the shingles A by suitable means such as a pair of oppositely disposed brushes 46 between which the shingles are adapted to pass edgewise as shown by Fig. 3. The brushes 46 are adjustably mounted so that they may be moved toward each other as the bristles 48 thereof are worn away by frictional contact with the shingles. The supporting means for each brush 46, consists, in the present instance of stud bolts 50 and nuts 52, which latter are threaded upon the former. The adjacent ends of the stud bolts 50 are secured to angle-irons 54 forming the upper longitudinal portion of the skeleton frame 4 and spaced apart to leave the intervening slot 56.

The brushes 46 are supplied with paint or stain from a suitable mixer 58 by means of a pump 60, a feed pipe 62 leading from the lower portion of the mixer 58 to the pump 60, and a pipe 64 leading from the pump 60 to discharge nozzles 66, all of which are located in the housing 2. The nozzles 66 extend upwardly between the bristles 48 of the brushes 46, Fig. 6, and discharge against spreaders 68 located at the upper portion of the brushes for directing the paint or stain downwardly over the bristles 48. The nozzles 66 are flexible so that they may be moved towards or away from each other when the brushes 46 are adjusted upon the stud bolts 50 and one of the nozzles 66 is provided with a valve 70 for cutting off the paint or stain to the respective brush when it is desired to coat but one side of the shingles. The pump 60 is driven independently of the conveyor 8 by suitable means such as a motor 72, sheaves 74 and 76 and a belt 80.

The feed pipe 62 is provided with a union 82 so that it may be uncoupled from the pump 60 when it is desired to swing the mixer 58 outwardly from the housing 2, Fig. 8, preparatory to supplying said mixer with paint or stain and so that it may be conveniently cleaned when desired. Before uncoupling the feed pipe 62 from the pump 60, a valve 84 connected to said feed pipe 62, may be closed to retain any paint or stain present in the mixer 58. In order that the mixer 58 may be readily swung outwardly or inwardly it is mounted upon hinges 86 and 88 and rails 90, which latter lead to an opening 92 in one side of the housing 2. The opening 92 is normally closed by a door 94 to exclude dust and other foreign matter from the interior of the housing 2. The door 94 is connected to the housing by a hinge 96 so that said door may be swung upwardly out of the way when opened.

The mixer 58 is equipped with a shaft 98 provided with an agitator 100 for mixing the ingredients constituting the paint or stain. The shaft 98 is driven independently of the conveyor 8 and the pump 60 by a motor 102, gear wheels 104 and 106, a shaft 108 and gear wheels 110 and 112. As shown the foregoing driving mechanism is mounted upon the mixer 58 to swing outwardly or inwardly therewith so that the agitator 100 may be driven while the mixer is in either position. The gear wheel 112 is secured to the agitator shaft 98 by means of a set screw 116 so that said gear wheel may be lifted from said shaft when it is desired to remove the lid 114 from the mixer 58 preparatory to filling or cleaning out the latter.

After a coat of paint or stain has been applied to one or both sides of the shingles A by the brushes 46, it is smoothed off to approximately uniform thickness and the surplus paint or stain

is removed by a plurality of brushes 120 spaced a suitable distance to the rear of the brushes 46. The brushes 120 are somewhat similar to the brushes 46, excepting that they are arranged at an angle to the shingles instead of parallel therewith. The brushes 120 are adjustably connected to the angle irons 54 by studs 122 and nuts 124 so that said brushes may be adjusted toward each other as the bristles become worn.

The surplus paint or stain dripping from the shingles A and the brushes 46 and 120 falls into troughs 126 and 128 which slope downwardly from the ends of the housing 2 to a spout 130, which latter discharges the surplus paint or stain into the mixer 58 for reuse through an opening 132 in the lid 114. The entrances to the spout 130 and the opening 132 have screens 134 and 136, respectively, to catch any splinters or other foreign matter removed from the shingles by the brushes 46 and 120. The troughs 126 and 128 are nearly as wide as the interior of the housing 2 to catch the surplus paint or stain and prevent it from splashing upon the mechanism located in the lower portion of the housing 2.

In order to enhance the appearance it is sometimes desirable to apply a variegated color to that portion of each shingle which is to be exposed to the weather when the shingle is laid upon a roof. The variegated color is obtained by applying paint of one color to the shingles with the brushes 46 and then spraying paint of another color by suitable means not shown, over the first coat of paint as the shingles travel behind a shield 138 which is suspended in the rear part of the housing by stud bolts 140 projecting from the adjacent angle iron 54. The shield 138 prevents wastage of the sprayed paint as it is of such size as to cover all but that portion which is exposed to the weather when the shingles are laid upon the roof.

Briefly stated the operation is as follows: The shingles A are placed one by one between the guides 30 and 38 and then pushed between the belts 10 of the conveyor 8 which carries the shingles to the rear end of the housing 2. In their passage through the housing the shingles are coated with paint or stain supplied to one or both of the brushes 46, as preferred, by the pump 60 which draws the paint or stain from the mixer 58 through the pipe 62 and forces it to one or both brushes 46 through the pipe 64 and the nozzles 66. Some of the surplus paint or stain drips from the shingles into the trough 126 which conducts it back to the mixer 58 for reuse. As the shingles pass between the brushes 120 the paint or stain is smoothed uniformly upon the surface of the shingles and more of the surplus paint or stain is brushed off and falls into the troughs 126 and 128 which conduct it back to the mixer 58. As the coated shingles are discharged from the rear end of the housing 2 by the conveyor 8, means are provided for receiving said shingles, but since such means forms no part of the present invention it was not deemed necessary to show or describe the same.

When the guide 30 is lowered the shingles A are also lowered as they pass through the housing 2, so that more of their surface is exposed to the brushes 46, and when said guide is raised the shingles pass through the housing on a higher plane so that less of their surface will contact the brushes 46.

From the foregoing description it will be understood that I have provided a mechanism which is well adapted for the purpose intended, and

while I have shown and described one embodiment of my invention I reserve all rights to such other forms and modifications thereof as properly fall within the spirit and scope of the invention as claimed.

Having thus described my invention, what I claim and desire to secure by Letters Patent, is:

1. A mechanism of the character described comprising a housing having a longitudinal slot

10 in its upper wall communicating with vertical inlet and outlet slots in its respective end walls for the passage of shingles, a conveyer for conducting the shingles through said slots, and means within the housing for applying paint or 15 stain to the surface of the shingles.

2. A mechanism of the character described comprising a housing, having a slot in its top portion, a conveyer for conducting shingles through said housing, a channel bar supported 20 above the slot in the housing for maintaining the upper edges of the shingles in longitudinal alinement, and means within the housing for applying paint or stain to the surface of the shingles.

3. A mechanism of the character described comprising a housing, having a slot in its top portion, a conveyer for conducting shingles through said housing, channel bar guide means supported above the slot in the housing for maintaining the upper edges of the shingles in longitudinal alinement, brackets extending upwardly from the housing, means adjustably connecting the channel bar guide means to said brackets so that said channel bar guide means may be raised or lowered to accommodate shingles of 35 different lengths, and means within the housing for applying paint or stain to the surface of the shingles.

4. A mechanism of the character described comprising a housing having a longitudinal slot 40 in its upper wall communicating with vertical inlet and outlet slots in its respective end walls for the passage of shingles, a guide member secured to the front wall of the housing for directing the shingles into the vertical inlet slot, a guide member supported above the longitudinal slot and the first-mentioned guide member and extending longitudinally of the housing for maintaining the upper edges of the shingles in horizontal alinement as they pass through the housing, a conveyer for conducting the shingles 45 through said slots, and means within the housing for applying paint or stain to the surface of the shingles.

5. A mechanism of the character described comprising a conveyer for carrying a plurality of vertically arranged shingles disposed side by side, a vertically disposed brush for applying paint or stain to said shingles, a nonperforate nozzle extending longitudinally of the brush for discharging paint or stain from its upper end, a spreader 55 on the upper end of the brush and against which the paint or stain is discharged and thereby spread over the paint or stain applying surface of said brush, and means for supplying the nozzle with paint or stain.

6. In a mechanism of the character described, a pair of endless belt conveyers arranged side by side and adapted to frictionally engage and carry between them vertically disposed shingles spaced one behind another, a pair of suitably supported 5 pulleys around which each conveyer travels, means for driving one of said pulleys, and means for applying a liquid to said shingles as they are advanced by the conveyers.

7. In a mechanism of the character described, 10 a pair of endless belt conveyers arranged side by side and adapted to frictionally engage and carry between them vertically disposed shingles spaced one behind another, a pair of suitably supported pulleys around which each conveyer travels, 15 means for driving one of said pulleys, guide means supported above the conveyers and adapted to maintain the upper edges of the shingles in horizontal alinement with each other while being carried by the conveyers, and means for applying a liquid to said shingles as they are advanced by the conveyers.

8. In a mechanism of the character described, 20 a pair of endless belt conveyers arranged side by side and adapted to frictionally engage and carry between them vertically disposed shingles spaced one behind another, a pair of suitably supported pulleys around which each conveyer travels, 25 means for driving one of said pulleys, guide means arranged above the conveyers and adapted to maintain the upper edges of the shingles in horizontal alinement with each other while being carried by the conveyers, supporting means adjustably engaged by said guide means 30 so that the latter may be raised or lowered, means 35 for securing said guide means at any point of its adjustment, and means for applying a liquid to said shingles as they are advanced by the conveyers.

9. In a mechanism of the character described, 40 a pair of endless belt conveyers arranged side by side and adapted to frictionally engage and carry between them vertically disposed shingles spaced one behind another, a pair of suitably supported pulleys around which each conveyer travels, 45 means for driving one of said pulleys, means for applying a liquid to said shingles as they are advanced by the conveyers, and spaced brushes arranged at an angle to the shingles and adapted to remove surplus liquid from said shingles. 50

10. In a mechanism of the character described, 55 a pair of endless belt conveyers arranged side by side and adapted to frictionally engage and carry between them vertically disposed shingles spaced one behind another, a pair of suitably supported pulleys around which each conveyer travels, 60 means for driving one of said pulleys, means for applying a liquid to said shingles as they are advanced by the conveyers, a mixer from which the liquid is supplied to the liquid-applying means, and trough means arranged beneath the shingles and leading to said mixer.

MARK H. JENKINS, SR.
